AUTOMOBILE RADIATOR CAP TOOL

Philip A. Heaver, Newtown Square, Pa. (1/2 Car Buddy Corp., 250 Rock Hill Road, Bala-Cynwyd, Pa. 19004)

Filed Nov. 6, 1970, Ser. No. 25,860

Term of patent 14 years

Int. Cl. D8—05

U.S. Cl. D8—21

FIG. 1 is a view in perspective of the automobile radiator cap tool as seen from the top;

FIG. 2 is a view in perspective of the tool as seen from the bottom;

FIG. 3 is a top plan view of the tool;

FIG. 4 is a side elevational view of the tool;

FIG. 5 is a bottom plan view of the tool;

FIG. 6 is a view in elevation of the tool as seen from one end thereof; and

FIG. 7 is a view in elevation of the tool as seen from the other end thereof.

I claim:

The ornamental design for an automobile radiator cap tool, as shown.
